UNITED STATES PATENT OFFICE.

JOHN H. LESTER AND GEORGE H. LESTER, OF NEW YORK, N. Y.

TROLLEY-WHEEL.

SPECIFICATION forming part of Letters Patent No. 635,262, dated October 17, 1899.

Application filed January 31, 1899. Serial No. 703,970. (No model.)

To all whom it may concern:

Be it known that we, JOHN H. LESTER and GEORGE H. LESTER, citizens of the United States, and residents of New York, (Brooklyn,) 5 in the county of Kings and State of New York, have jointly invented a new and useful Improvement in Trolley-Wheels, of which the following is a specification.

Our invention relates to an improvement 10 in trolley-wheels in which the rim and body of the wheel are composed of soft electrical conducting metal—such, for instance, as brass—provided with a central socket, a cylindrical sleeve of hard metal forming a lining 15 for the curved wall of the said socket, a disk of hard metal forming a lining for the base of the socket, a removable hard-metal cover for the mouth of the socket, and a series of bearing-rollers held in position within the 20 sleeve by the cover.

A practical embodiment of our invention is represented in the accompanying drawings, in which—

Figure 1 represents a side view of our improved trolley-wheel and a portion of its support. Fig. 2 is an edge view of the same. Fig. 3 is a central section in the plane of the line 3 3 of Fig. 2, the said section being taken at right angles to the wheel-bearing spindle; 30 and Fig. 4 is a transverse vertical section in the plane of the line 4 4 of Fig. 1.

The forked end of the trolley-wheel support is denoted by A, the branches of the fork within which the spindle B is mounted 35 being denoted by a a'.

The rim and body portion of the wheel are denoted by C, and they may be made of some suitable soft electrical conducting metal, as is usual—such, for instance, as brass. The rim 40 is provided with the usual circumferential groove c. One side of the rim and body portion C of the wheel is provided with a recessed seat c' for the reception of a removable cover, to be hereinafter described. The rim 45 and body portion are further provided with a central cylindrical socket c², extended inwardly from the seat c' to a point near the opposite side of the rim and body portion. A disk D, of hard metal, is fitted into the base of 50 the socket c² and forms a lining therefor. A cylindrical sleeve d is inserted within the

central socket c², which sleeve is of sufficient width to form a lining for the curved wall of the socket, the inner end of said sleeve resting against the disk D and the outer end 55 preferably flush with the base of the seat c'.

d' represents a hard-metal cover for the mouth of the socket, which cover is removably secured within the seat c' by screws d², which enter the body portion C of the wheel. 60 The cover d' is provided with a central hole d³, the lining-disk D with a central hole d⁴, and the body portion with a central hole c³, corresponding with the holes d³ and d⁴. The spindle B passes through the holes d³ d⁴ c³, 65 which holes are of slightly-greater diameter than the spindle.

An annular series of hard-metal bearing-rollers F are located within the central socket in the wheel and are interposed between the 70 cylindrical sleeve d and the spindle B. These bearing-rollers are held in their position by the removable hard-metal cover d'. Anti-friction-washers E are interposed between the sides of the wheel and the branches of the 75 forked support around the spindle B.

By the structure hereinabove described the life of the trolley-wheel is materially increased, its conductivity is not impaired, and it runs with much greater freedom, because 80 of the use of the antifriction-bearing. All of the wearing parts of the bearing are made of hard metal, while the body and rim of the wheel are still made of a soft electrical conducting metal, so that the wear upon the conducting-wires is reduced to a minimum. By thus mounting the wheel so that it will not become clogged and stopped the danger of scoring the groove c is obviated.

It is evident that slight changes might be 90 resorted to in the form and arrangement of the several parts without departing from the spirit and scope of our invention. Hence we do not wish to limit ourselves strictly to the structure herein set forth; but 95

What we claim is—

In combination, a trolley-wheel comprising a rim and body of soft electrical conducting metal provided with a central cylindrical socket extended inwardly from one side of 100 the body a distance sufficient to leave a portion of the body between the base of the

socket and the other wall of the body, a cylindrical sleeve of hard metal forming a lining for the curved wall of the socket, a disk of hard metal forming a lining for the base 5 of the socket, a cover of hard metal for the mouth of the socket removably secured to the body, a spindle passing through central openings in the cover the disk and the body, a support for the spindle and an annular series of bearing-rollers interposed between the 10 said spindle and sleeve for forming an anti-

friction-bearing for the wheel, substantially as set forth.

In testimony that we claim the foregoing as our invention we have signed our names, in 15 presence of two witnesses, this 30th day of January, 1899.

JOHN H. LESTER.
GEORGE II. LESTER.
